CLAIM

The ornamental design of a radio, as shown and described.

DESCRIPTION

FIG. 1 is a front elevation view of a radio showing my new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a rear elevational view thereof;

FIG. 7 is a left side elevational view of an alternate embodiment of FIG. 1, the remaining views being similar to the first embodiment, except for the control switch on the left side.
